DESIGN FOR AN ELECTRIC VIBRATOR

Abe O. Samuels, Rochester, N. Y., assignor to
Samson-United Corporation, Rochester, N. Y.

Application December 10, 1935, Serial No. 60,001

Term of patent 14 years

To all whom it may concern:

Be it known that I, Abe O. Samuels, a citizen of the United States, residing at Rochester, in the county of Monroe and State of New York, have invented a new, original, and ornamental Design for Electric Vibrators of which the following is a specification, reference being had to the accompanying drawing, forming a part thereof.

Figure 1 is a side elevation of the electric vibrator showing my new design.

Figure 2 is an end elevation of the electric vibrator showing my new design.

The dominant feature of the design resides in the portion illustrated in full lines in the figures of the drawing.

I claim:

The ornamental design for an electric vibrator as shown and described.

ABE O. SAMUELS.
